UNITED STATES PATENT OFFICE.

ALVIN D. PUFFER, OF BOSTON, MASSACHUSETTS.

REFRIGERATOR.

SPECIFICATION forming part of Letters Patent No. 255,456, dated March 28, 1882.

Application filed March 13, 1880. Renewed February 9, 1882. (No model.)

To all whom it may concern:

Be it known that I, ALVIN D. PUFFER, of Boston, county of Suffolk, and State of Massachusetts, have invented certain new and useful Improvements in Refrigerators, of which the following is a specification.

This invention relates to refrigerating structures or devices mainly for use in fountains for soda and other aerated waters, in which are employed swinging doors or receptacles for the support of the sirups or other liquids to be cooled, the interior of such doors communicating with the ice-chamber of the structure and being hinged to the latter in order to be swung open and expose the vessels within or upon them, and to permit such vessels to be inspected or removed and refilled, or to be cleaned, as the case may be, and also to permit of introduction of ice to the ice tank or chamber.

An instance of the class of refrigerators to which my present improvements relate is shown in an application for a patent filed by myself prior to this application and now pending.

The drawings accompanying this specification represent, in Figure 1, an isometric view, and in Figs. 2 and 3 sections, of a refrigerating apparatus containing my invention; Fig. 4, section of shifting bottom and slide-carrier.

In said drawings, A represents the case of the structure, being in general terms an upright oblong rectangular box with an opening, B, at top, which in most instances is covered by the counter of the shop in which the structure is placed, but which in other instances may be provided with a cover and permit of introduction of ice through it to the refrigerating-chamber below, the interior A' of the case A being for the greater part devoted to the purpose of an ice-receptacle and refrigerating-chamber, a portion of the upper front part of such case A being occupied by the doors before alluded to, and which will be hereinafter explained, the waste-water overflow-opening being arranged at the bottom of the ice-tank, as shown at a.

The lower front part of the structure A is converted into a bay, D, the top of which is open, as shown at E, except when closed by the doors, and it is through this opening E

that ice is usually introduced to the chamber A'. Openings b b, &c., are made in the front wall, c, of the structure to permit of passage of cold air from the chamber A' to the interior of the receiving-doors, which contain the bottles or vessels holding the liquid to be cooled. These swinging doors, or "closets," as they may appropriately be termed, are two in number in the present instance, though more or less than two may be employed, and are shown at F and G, respectively, as shallow boxes, with the openings on the inside, and covering the cold-air apertures b, and hinged at their inner edge to the central part of the front of the structure, which in this case is a hollow post, d, adapted to receive one of the cooling-vessels, the doors being closed by a suitable latch, which insures a sufficiently-tight joint to prevent escape of cold air from the interior; or the usual means may be employed for packing the joint between the doors and remainder of the structure. The interior of each closet F and G is divided into a series of vertical cells, e e, &c., each of which is adapted to contain and support in an upright position a bottle, f, or other vessel to contain the sirups or other liquids to be cooled, the common bottom g of the cells being of such height in most instances as to cause the neck of the bottle to protrude above the top plate, h, of the closet, in order that it may be reached by the shopman and lifted out of its receptacle, an opening, i, being made in the said top plate, h, over each cell, to permit of access to and removal of the bottle. Each opening i is to be provided with a cover of some proper construction, which shall close the opening with an air-tight joint and inclose the neck of the bottle and the cap or cover which closes the latter. These covers to the openings i may be of various constructions, and I do not limit myself to any one especial form. For instance, j represents a cover which is simply fitted at its lower part into the opening i. K represents the cover as hinged to the top plate of the closet at one side of the opening, each cover being hollow to inclose the neck and cover of the bottle. I prefer, however, and am now using, a cover the construction of which is shown at l in the drawings. This cover is simply a flat drop-valve, preferably padded on

its under side to insure a tight joint about the adjacent opening *i*, and resting by its own weight upon the top of the plate *h*, such cover *l* being hinged at its rear edge to the front wall of the structure, in order to connect it with the latter, this hinge being so arranged that when the cover is left alone it stands in a horizontal plane and in such a position with respect to the door or closet *G* that as the latter is closed it wipes against and slightly raises the cover, which settles down about the opening *i*. The valve or cover *l* may be of metal or may be weighted to cause it to act effectively.

15 It will be seen that the bottom *d'* of the cell *e'*, with which the cover *l* operates, is so arranged that the neck of the bottle *g'* resting upon it does not protrude through the top plate, *h*, but is practically flush with it; and in order that the bottle *g'* may be raised into a position to be readily grasped and removed when occasion requires without necessity of opening the door, I make such bottom shifting or movable and capable of sliding vertically within its cell. In the present instance the bottom *d'* is affixed to a support, *m*, sliding upon the front of the door and composed of two flat elastic plates, *n o*, one disposed upon the inside and the other upon the outside, and united by the shank of a knob or button, *p*, which plays in a slot, *q*, in the door-front, the two plates serving to cover the slot and prevent escape of cold air from the interior of the closet.

35 By means of the knob *p*, which is located upon the outside of the closet-front, the shifting bottom, and with it the bottle, may be raised into such a position that the upper portion of the bottle protrudes through the top 40 of the door, and so that it may be readily grasped and lifted out and replaced.

I do not confine myself to the precise con-

struction of the bottom or support *d'* as herein described, as I consider my invention in this respect to consist in a support to the bottle which is capable of being raised and lowered with respect to the opening in the top plate and the valve *l*, and be held by the springs *n* and *o* or their equivalents in any required position.

To enable the door or closet to readily close below the valve or cover *l*, it may be well to bevel off the lower front edge of such cover, or the rear upper edge of the top of the door, or both.

I claim—

1. The combination, with the refrigerating-box *A*, provided with bay *D*, of one or more doors containing cells provided with removable covers, as described, said cells, when the door is closed, fitting over the top of the bay *D* and up against the body of the refrigerator, substantially as hereinbefore set forth.
2. In combination with the refrigerator-box and the door provided with cells, the cover or covers *l*, hinged to the box in position to drop over and cover the cell-openings when the door is closed, substantially as hereinbefore set forth.
3. In combination with the refrigerator and door for closing the same, one or more cells upon the interior of the door, provided with a vertically-movable interior bottom or support, and means, substantially as described, for adjusting and holding said bottom or support, substantially as hereinbefore set forth.
4. The combination of the bottom *d'* and springs *n o*, united by the button *p*, for the purpose of raising and sustaining the bottom in any position, substantially as stated.

ALVIN D. PUFFER.
